POLISHING MACHINE

Joel Goldschein, East Northport, N.Y., assignor to Joel Goldschein, Jericho, and Gulfport Chemical Corporation, Plainview, N.Y.

Filed Nov. 7, 1966, Ser. No. 4,564

Term of patent 14 years

(Cl. D37—1)

FIG. 1

FIG. 2

FIG. 3

FIG. 1 is a top plan view of a polishing machine, showing my new design;

FIG. 2 is a side elevation view thereof;

FIG. 3 is a bottom plan view thereof.

The side of the polishing machine not shown is substantially the same in appearance as the side shown.

The dominant features of my design reside in the portions shown in full lines.

I claim:

The ornamental design for a polishing machine, as shown and described.
